UNITED STATES PATENT OFFICE.

WILLIAM GOFF ROBEY, OF GRAFTON, WEST VIRGINIA.

ROTARY TOOTHBRUSH.

Application filed March 29, 1926. Serial No. 98,051.

This invention is an improvement in tooth brushes, and more particularly in brushes of the rotary type.

The tooth brushes usually employed do not thoroughly cleanse the teeth, because it is difficult to apply the brush to all parts of the teeth in the approved manner, that is, with the bristles moving from the roots towards the points, and when the brush is applied with the usual reciprocating movement, the interstices between the teeth are not reached.

Rotary brushes as heretofore constructed have not been suitable for individual use, because of complications in construction or because of bulk, and one of the primary objects of the present invention is the provision of a light weight, small and compact motor operated brush of the rotary type, wherein the motor is manually operated, and of a size to be conveniently held in one hand and operated by the said hand, leaving the other hand free to manipulate the brush.

Another object is the provision of a simply constructed brush of the character specified which may be economically manufactured, and sold at a reasonable price.

With these and other objects in view the invention consists in the construction and novel combination of parts fully described hereinafter, illustrated in the accompanying drawings, and pointed out in the claims appended hereto, it being understood that various changes in the form, proportion, size and minor details of construction within the scope of the claims, may be resorted to without departing from the spirit of the invention.

In the drawings forming a part hereof:—
40 Figure 1 is a side elevation with the motor casing in section.

Figure 2 is a section on the line 2—2 of Figure 1.

Figure 3 is a longitudinal section through the brush supporting element.

Figure 4 is a section on the line 4—4 of Figure 3.

The present embodiment of the invention comprises a brush and its supporting mechanism in which the brush is rotatably mounted, and a motor for driving the brush, the motor being manually operated and connected to the brush by a flexible shaft in the usual manner. The motor also is of such size that it may be easily held in the

hand, and operated while so held, leaving the other hand free to manipulate the brush.

The motor is held in a casing 1, which preferably is of cylindrical construction, and of any suitable material. The motor includes a shaft 2, journaled in the end walls of the casing at the center thereof, and the shaft carries a fly-wheel 3 of sufficient weight to insure smooth, even running of the motor when it is in operation.

At one end of the shaft 2 a pinion 4 is secured, meshing with another pinion 5 on a jack or stub shaft 6 journaled in the end of the casing, and in a bearing bracket 7 secured to the casing wall. The jack shaft 6 extends through the casing wall, and outside of the wall carries a coupling 8, for connection with the flexible shaft to be described.

At the opposite side of the fly-wheel 3 from the pinion 4, a second pinion 9 is secured to the shaft 2, and the pinion meshes with a pinion 10 on a counter-shaft 11, journaled in a substantially U-shaped bracket 12 extending radially from the casing wall. The pinion 10 is relatively large, and a second pinion 13 relatively small is rigidly connected with the pinion 10.

This pinion 13 meshes with a gear wheel 14, at one end of a hub or sleeve 15 which is loosely journaled on the shaft 2. The sleeve 15 is provided at its other end with a ratchet wheel 16, and it will be evident that when the ratchet wheel is rotated, in a manner to be presently described, the shaft 2 will be driven through the gears 14, 13, 10 and 9. The said gears provide a speeding up gear train for rotating the shaft 2 at a speed relatively high as compared with the speed of rotation of the sleeve 15. The motion of the shaft 2 is transmitted to the jack shaft 6, by the gears 4 and 5, and at a yet higher rate as applied to the shaft 6.

The ratchet wheel 16 is rotated by means of a pawl 17. This pawl is pivoted to an arc shaped member 18, in the form of a plate of material similar to that of the casing 1, and the said plate is slidably mounted on the inner face of the side wall of the casing rotating on the shaft 2. The plate has radial extensions 18¹ which are journaled on the shaft, and the plate is free to swing in an arc shaped path limited by a handle member to be presently described. It will be noticed, referring to Figure 2, that the cas-

ing side wall is cut away as indicated at 19 for enabling the movement of a substantially U-shaped handle 20 connected with the plate, and extending through the opening.

5 The handle 20 has the arms thereof secured to the plate 18, and on the body portion of the handle a grip 21 is mounted, the said grip being of any suitable material, as for instance, soft rubber or the like. An-
10 other handle 22 of U-shape is connected with the casing 1. The arms of the handle 22 may be secured to the casing 1 in any suitable manner, or they may be integral therewith, as may be found desirable in practice, and
15 the body of the handle 22 also carries a soft rubber grip 23.

A spring 24 is arranged between the plate 18 and the casing 1, and the spring is de-
20 signed to hold the plate and the handles in normal position. When the grips 21 and 23 are moved toward each other, the pawl
25 engages the teeth and rotates the ratchet wheel. When the pressure on the grips is released, the spring moves the plate 18 in the opposite direction, and the pawl slips idly over the teeth of the ratchet wheel. The movement of the ratchet wheel is imparted to the jack shaft 6, and to the brush to be presently described, the movement of the
30 shaft 2 being steadied, governed and made uniformed by the fly wheel 3.

The tooth brush proper comprises a cylindrical body 25, having tufts 26 of bristles extending radially therefrom. The bristles
35 may be of any desired nature and character, and they are preferably so arranged that the contour of the brush as a whole is elliptical. The body 25 has a reduced axial extension 27, which at the end remote from the brush is polygonal in cross section, to engage within a socket 28 on a shaft 29. The shaft 29 is journaled in a trough shaped casing 30 of any suitable material, having at the end adjacent to the brush a spoon bowl shaped enlargement 31.

The enlargement 31 is of dimensions to cover a little more than half of the brush, and acts as a shield to protect the soft tissues of the mouth from the action of the bristles. Roller bearings 27' are provided for supporting the extension 27 in the trough, and the shaft 29 is relatively fixed in the trough, so far as regards bodily movement.

50 55 That end of the trough remote from the enlargement 31 has connected therewith, threadedly as shown, a tubular extension 32. The remote end of this extension is threaded to engage within a coupling 33 at one end of a flexible shaft 34 of usual construction, the other end of the shaft being adapted to engage within the coupling 8 before mentioned.

60 Referring to Figures 1 and 3, it will be noticed that the connection between the shafts 34 and 29 is the usual socket connec-

tion, and the coupling 33 by its engagement with the tubular extension 32 prevents disengagement of the shafts. A similar connection is provided at 8, between the jack shaft and the flexible shaft. The coupling 8 is a 70 threaded cap which engages the casing of the flexible shaft, holding the socketed parts together. The engagement between the jack shaft and the rotary part of the flexible shaft at 8 is similar to that shown at the 75 left of Figure 3 between the shafts 34 and 29.

To disengage the flexible shaft from the jack shaft, the cap is released from the flexible shaft, after which the shafts may be moved away from each other. This is also 80 true with the connection at 33. Referring to Figure 1 it will be noticed that housing members 35 are arranged at the ends of the shaft 2, and these housing members have oil holes by means of which the motor may be 85 lubricated.

In operation, the brush is held in either hand, grasping the handle 52. The motor is held in the other hand, the hand engaging the grips 21 and 23. When the grips are 90 pressed together, the ratchet wheel is rotated, the motion being transmitted to the brush. When the pressure on the grips is relaxed, the spring returns the parts to normal position. 95

It will be noticed referring to the drawing, that the entire length of brush and handle is in smooth regular lines, with no rough edges, corners or the like to touch the soft tissues of the mouth. That portion of the handle adjacent to the flexible shaft is provided with a tubular grip fitting closely thereof, the said grip being indicated at 52, and the edges of the trough shaped portion of the handle are rounded. The free edge of the bowl is beaded or enlarged as shown at 53 entirely around the bowl. 100

105 What is claimed as new is:

1. A motor for rotary tooth brushes, adapted to be held in one hand and operated thereby, including a cylindrical casing having a radial handle member and an opening in the side wall adjacent thereto, a shaft at the axis of the casing and provided with a flywheel, a sliding plate mounted within the casing at the opening and closing the same, said plate provided with a handle member extending through the opening, the handle members adapted to be gripped by the hand supporting the motor to move them toward each other, a spring acting on the plate to move the handle members apart, a pawl and ratchet connection between the plate and the shaft, and a coupling shaft driven by the first named shaft. 110

115 120 125 130 2. A motor for rotary tooth brushes, adapted to be held in one hand and operated thereby, including a cylindrical casing having a radial handle member and an opening in the side wall adjacent thereto, a shaft at

the axis of the casing and provided with a flywheel, a sliding plate mounted within the casing at the opening and closing the same, said plate provided with a handle member extending through the opening, the handle members adapted to be gripped by the hand supporting the motor to move them toward each other, a spring acting on the plate to move the handle members apart, a ratchet wheel loose on the shaft, the plate having a pawl engaging the wheel when the handle

members are moved toward each other, a speeding up gear train between the ratchet wheel and the shaft, and a coupling shaft parallel with the first named shaft and having a driving connection therewith, and extending through one end wall of the casing. ¹⁵

Signed at Grafton, in the county of Taylor, and State of West Virginia, this 17th day of March A. D. 1926.

WILLIAM GOFF ROBEY.
